[57] CLAIM

The ornamental design for a watering can, substantially as shown.

DESCRIPTION

FIG. 1 is a perspective view taken from the top, front and right side of a watering can showing my new design;

FIG. 2 is a perspective view taken from the top, rear and left side thereof;

FIG. 3 is a top plan view thereof;

FIG. 4 is a right side elevational view thereof;

FIG. 5 is a bottom plan view thereof;

FIG. 6 is a sectional view taken along lines 6—6 of FIG. 3; and

FIG. 7 is a sectional view taken along lines 7—7 of FIG. 3.
